UNITED STATES PATENT OFFICE.

HUGH MERIDITH HINER, OF FORT SMITH, ARKANSAS.

POTASSIUM-COMPOUND-RECOVERING APPARATUS.

1,290,194.

Specification of Letters Patent. Patented Jan. 7, 1919.

Application filed November 8, 1917. Serial No. 200,908.

To all whom it may concern:

Be it known that I, HUGH MERIDITH HINER, a citizen of the United States, residing at Fort Smith, in the county of Sebastian and State of Arkansas, have invented certain new and useful Improvements in Potassium-Compound-Recovering Apparatus, of which the following is a specification.

10 My invention relates to an apparatus adapted for use in recovering potassium compounds from burned material, and the smoke therefrom.

15 An important object of the invention is to provide apparatus of the above mentioned character, which is simple in construction, inexpensive to manufacture, strong and durable.

20 Other objects and advantages of the invention will be apparent during the course of the following description.

25 In the accompanying drawings forming a part of this specification and in which like numerals are employed to designate like parts throughout the same,

Figure 1 is a central vertical sectional view through the apparatus embodying the invention,

30 Fig. 2 is a horizontal sectional view taken on line 2—2 of Fig. 1,

Fig. 3 is a side elevation of the apparatus, and,

Fig. 4 is a plan view of the same.

35 In the drawings, wherein for the purpose of illustration is shown a preferred embodiment of my invention, the numeral 5 designates a shell constituting the body portion of the apparatus. This shell is formed of fire brick or other suitable material.

40 Arranged within the lower portion of the shell 5 are spaced horizontal grate bars 6, constituting a support for the material to be burned. Disposed beneath the grate bars 6 is an ash-pit or chamber 7, preferably 45 frusto-conical in cross-section and decreasing in diameter downwardly. The burned material or ashes is withdrawn from the ash-pit 7 through the opening which is normally closed by a door 8, shown more clearly 50 in Fig. 3.

I preferably employ a force draft and for this purpose a horizontal air supply pipe 9 leads into the ash-pit 7, and has a cap or nozzle 10 arranged slightly above the grate-bars 55 6, as shown. The air pipe 9 receives the air from the rotatable fan or blower 11,

which is driven by a sprocket wheel 12 receiving its rotation from an outwardly extending sprocket chain 13.

The portion of the shell 5 above the grate-bars 6 constitutes a combustion chamber 14, preferably having inclined walls 15 and 16, as shown. Access is had to the interior of this chamber through an opening, normally covered by a door 14', as shown. 65

The material to be burned, which is finely divided, such as cotton bolls, hardwood sawdust, etc., is fed into the upper end of the combustion chamber 14 through a pipe 17, discharging into an opening 18 passing 70 through the top 19 and discharging into the combustion chamber 14. Arranged within the pipe 17 is a spiral conveyer 20, which is driven by a horizontal shaft 21, having a sprocket wheel 22 secured thereto. This 75 sprocket wheel is engaged by the sprocket chain 13.

The smoke or gaseous products of combustion, which are rich with potassium compounds, discharge from the upper portion 80 of the combustion chamber 14 into a pipe or take off conduit 23, provided at its opposite end with a down-turned neck 24. This down-turned neck passes through the upper closed end of a water holding tank 85 25, and is disposed beneath the water level therein. The water soluble potassium compounds go in solution into the water while the hot air or gases are free to escape to the atmosphere through a pipe 26. The 90 fresh water may be supplied to the tank 25 through a pipe 27 having a cut-off valve 28 therein.

Connected with the lower end of the tank 25 is a draw-off pipe 29 connected with a 95 horizontally arranged steam supply pipe 30. The steam supply pipe 30 projects into the upper portion of the combustion chamber 14, as clearly shown in Fig. 1 and is provided therein with a spray nozzle 31. The 100 pipe 30 has a cut-off valve 32. It is obvious that the steam pressure will force or inject the water having the potassium compounds in solution or suspension therein, into or through the nozzle 31, causing the same to 105 be sprayed into the upper portion of the combustion chamber 14, in proximity to or in contact with the wall 15. This sprayed liquid is more or less evaporated before it reaches the bottom of the combustion chamber and therefore does not materially impair the operation of the furnace. 110

The operation of the apparatus is as follows:

A fire is built upon the grate-bars 6 in the usual manner, and the spiral conveyer 20 is started which feeds material into the combustion chamber 14, such material falling upon the grate-bars 6 and is accordingly burned. The material from the pipe 20, which may be cotton bolls, hardwood saw-dust, or the like, constitute the real fuel for operating the furnace. The ashes of course will pass through or between the grate-bars and will be caught within the ash-pit 7. The smoke or gaseous products of combustion pass through the pipe 23 and are delivered into the tank 25, beneath the water level. The soluble potassium compounds in solution or suspension in this water are withdrawn with the water through the pipe 29, and forced or injected by steam passing through the pipe 30, into the upper portion of the combustion chamber, in a finely divided or sprayed form. This sprayed liquid descends within the combustion chamber 25 and is more or less evaporated at or before reaching the grate-bars, whereby the finely divided potassium compounds discharge upon the grate-bar and become mixed with the ashes.

30 It is to be understood that the form of my invention herewith shown and described is to be taken as a preferred example of the same, and that various changes in the shape, size, and arrangement of parts may be resorted to without departing from the spirit of the invention or the scope of the subjoined claims.

Having thus described my invention, I claim:

40 1. In apparatus for recovering potassium compounds, a main shell including a combustion chamber and an ash-pit arranged therebelow, means to feed material to be burned into the combustion chamber, a water holding tank, a smoke take off pipe having communication with the combustion chamber and discharging into the water holding tank, and means for withdrawing the water

from the water holding tank and discharging the same into the combustion chamber. 50

2. In apparatus for recovering potassium compounds, a main shell including a combustion chamber and an ash-pit arranged therebelow, means to feed material to be burned into the combustion chamber, a water holding tank, a smoke take off pipe having communication with the combustion chamber and discharging into the water holding tank, a discharge conduit connected with the tank, and a steam supply pipe having connection with the discharge conduit and extending into the combustion chamber and provided with means to spray the liquid therein. 55

3. In apparatus for recovering potassium compounds, a main shell having a combustion chamber, means whereby the ashes may be withdrawn from the shell, means to feed material into the combustion chamber, a water holding tank, a smoke take off pipe 60 having communication with the combustion chamber and discharging into the tank, a steam supply pipe extending into the upper end of the combustion chamber, and an outlet conduit connected with the tank and connected with the steam supply pipe. 75

4. In apparatus for recovering potassium compounds, a main shell having a combustion chamber, a conveyer for fuel discharging into the upper end of the combustion chamber, a smoke take off pipe leading into the top of the combustion chamber, a water holding tank receiving therein one end of the smoke take off pipes, an outlet pipe connected with the tank and discharging into 80 the upper end of the combustion chamber, and a force draft device for supplying air into the lower end of the combustion chamber. 85

In testimony whereof I affix my signature 90 in presence of two witnesses.

HUGH MERIDITH HINER.
